UNITED STATES PATENT OFFICE.

OLIVER RICE, OF EAST OAKLAND, CALIFORNIA.

RUG-MAKING MACHINE.

SPECIFICATION forming part of Letters Patent No. 595,113, dated December 7, 1897.

Application filed November 19, 1896. Serial No. 612,690. (No model.)

To all whom it may concern:

Be it known that I, OLIVER RICE, a citizen of the United States, residing at East Oakland, county of Alameda, State of California, have 5 invented an Improvement in Rug-Making Machines; and I hereby declare the following to be a full, clear, and exact description of the same.

My invention relates to an apparatus which 10 is especially designed for the manufacture of rugs in which threads or yarns are formed in loops upon a canvas or flexible foundation.

My invention consists in certain details of construction, which will be more fully explained by reference to the accompanying drawings, in which—

Figure 1 is a general view of my machine. Fig. 2 is a view of the central part of the table and its connections, a portion of it being 20 broken away to show the feed mechanism. Fig. 3 is a longitudinal section through the looper and connections, showing the stitch completed. Fig. 4 is a diagrammatic view of a finished portion of the rug.

In the operation of my machine the canvas or flexible foundation A is secured in a clamp B, which is slidable in a groove or guide C in the top of a table or support D. Secured to the front edge of this table is a supporting 25 frame or yoke E, the rear end of which is connected with a looper-guide G, within which the looper H is slidable to and from the clamp B. The looper is moved forward by a connecting-rod I, pivoted to its rear end and having its opposite end connected with one arm of a bell-crank lever J, which is fulcrumed near the front end of the frame or yoke E. The other arm of the bell-crank lever is connected by a rod K with a treadle L, centrally 30 fulcrumed, as shown at M. When this treadle is depressed by the foot of the operator, the action of the arm and bell-crank lever J will be to pull the looper forward.

The operation of the looper will be more 45 fully described hereinafter.

H' is a spring, one end of which is connected with the looper and the other with the yoke or frame E, so that when the treadle is released the spring will draw it back. A spring K' may also be attached to the connecting-rod K to insure the return of the treadle after 50 it is released from the operator's foot.

From the rear end of the treadle L a connecting-rod N extends angularly upward and connects with the lower end of a vertically- 55 slidable needle-carrier O, having a suitable guide P to insure its proper movement. This needle F moves upwardly through the table D and the fabric A, which is upon the table, and with such relation to the looper that the 60 latter will pass a projecting horn Q through the loop formed by the needle. This horn has a slot or channel made in it, within which is fulcrumed a tilting arm R, having a hook-shaped point R' near the front end. 65

Across the looper-guide G is fixed an arched piece S in such position that when the looper is drawn backward the upwardly-curved back of the arm R will engage this arch, and that will tilt the arm R, so as to lift the point R', 70 for the purpose to be now described.

The guide G has fixed to it two projecting spurs or guides T upon each side of and below the line of travel of the horn Q. The yarn U is inserted over these points T, which 75 serve as guides or supports, and is moved back until it engages with the point R', this point projecting enough below the horn Q for that purpose. The horn Q will have opened the needle-loop by its forward movement, as 80 previously described, and when it is retracted the hook R' will draw the yarn U backwardly through the needle-loop, and as the curved top of the arm R passes beneath the arch S it will be tilted, as previously described, so 85 that the hook R' will be released from the yarn U and allowed to move back, leaving the loop of the yarn thus formed passing through the loop of the needle-thread. This latter is then drawn tight by the downward 90 movement of the needle and the tension which is put upon the needle-thread, and the loop is thus tied or completed, as shown in Fig. 3. These yarn-loops are separated and regulated by means of fingers or teeth V of a "comb," 95 so called, which projects from the clamping-bar B, previously referred to, the needle passing up between these teeth successively. In order to advance the clamp, the comb, and the fabric transversely, so as to present it for 100 each reciprocation of the needle and to form the loops of the rugs successively, I have shown a rack having two sets of teeth W and W'. One set of these teeth points in one di-

rection and the other in the opposite direction.

X is a double-ended pawl suitably pivoted, as shown at Y, so that one end of the pawl 5 may be made to engage with the rack W and the other end with the rack W'. This rack-bar is fixed to the clamp and carrier B, and the pawl X is mounted upon a movable bar Z. This bar is actuated by a bell-crank lever 10 a, so as to be reciprocated, and when one point of the pawl engages the rack W the clamp will be made to travel in one direction by steps as the pawl engages the teeth successively. When tilted so that the opposite end of the 15 pawl engages the rack W', the clamp will be moved in the opposite direction. This serves to feed the clamp and the rug across the table by steps which are equal to the spaces between the teeth V, because the teeth of the 20 racks W W' are of the same length as these spaces, and when the fabric has been carried across to one side and loops formed across it the pawl X may be reversed and the movement of the carrier Z, upon which it is mounted, will reverse the movement of the carriage 25 and the fabric and return them to the opposite side of the table while another set of loops is being put in by the needle and shuttle. The pawl has springs b, which may be connected with it. When the spring which is 30 connected with one end of the pawl is so connected as to pull upon the pawl, it will act to engage one end of the pawl with one of the racks, and when the other end of the pawl is 35 acted upon the opposite end will be engaged with its rack. The movement of the pawl and its slide is effected by the movement of the treadle L, which operates the needle-bar O. This movement to advance in one direction 40 is effected by connecting one of the arms c of the bell-crank lever a with a rod d, connecting it with the treadle or some intermediate portion. The advance in the opposite direction is effected by connecting the rod d with 45 the opposite arm c', Fig. 2.

The needle-thread e passes through the eye of the needle F, leading through and beneath the table, and thence along a channel d', formed in the table adjacent to the guide- 50 channel C, and over a bobbin or spool g with a suitable tension device. The thread is also made to carry a weight h at a point intermediate between the bobbin and the needle, so as to draw the thread up and tie the loop of 55 the yarn U whenever the latter has been drawn through the needle-thread, as previously described.

The operation of the machine will then be as follows: The carriage or clamp B being at 60 one side of the table, so that the edge of the fabric A which forms the base of the rug is presented to the needle F, the looper is moved forward in its guide by pressing the foot upon the treadle L, and the rear end of the treadle 65 pushes the needle F up through the fabric and then moves the looper forward, forcing the horn Q through the loop formed between

the needle and its thread e. Now the yarn is fed over the spurs T and under the hook R' in horn Q, and when the pressure upon the treadle is relieved the parts are returned to their normal position by the action of the connected springs, and the horn, with its hook R', will be drawn backwardly, thus drawing the yarn U through the needle-thread in the form 70 of a loop, and as the needle is withdrawn the tension upon the thread e will cause it to bind the loop of the yarn which is thus left lying over a finger of the comb V and the surface of the fabric forming the base of the rug. 75 These movements are continued until the rug has been moved across the table by the action of the pawl and racks, when the rod d will be connected with the lever-arm c' and the tension of the springs engaging the pawl will 80 be changed, so that the opposite end of the pawl will engage its rack and the apparatus be returned toward the other side, the mechanism operating as previously described. Before this movement takes place, however, the 85 base or fabric A is advanced by loosening the holding-nuts B' of the clamp B, so that the fabric A can be moved forward a distance equal to that which it is desired to make between the rows of loops formed upon its 90 surface, after which it is again clamped in place, when the operation is proceeded with.

Having thus described my invention, what I claim as new, and desire to secure by Letters Patent, is—

1. In a rug-making machine, the combination of a table, having a guide or channel in its top, a clamp or carrier, movable in said guide and adapted to hold the fabric of the rug while it is being moved across the table, a slotted yoke extending transversely across the table and forming a horizontal guide, a looper slidable in said slotted yoke, a feed mechanism, a needle-carrier having a needle working upwardly through the fabric, a treadle and means connecting the opposite portions of the same with the looper and needle-carrier respectively.

2. In a rug-making machine, the combination of a table having a longitudinal guide or 115 channel in its top, a clamp or carrier fitted to slide in said guide and adapted to hold the fabric of the rug while it is being moved across the table, a slotted yoke extending transversely across the table and forming a 120 horizontal guide above the fabric, a looper slidable in the slotted yoke and having a horn which passes through the loop of the thread when the looper is advanced, a reversible feed mechanism, a needle-carrier having a 125 needle working upwardly through the fabric, a treadle and means connecting the opposite portions of the same with the looper and needle-carrier respectively.

3. In a rug-making machine, the combination of a channeled table, a clamp or carrier 130 slidable therein and adapted to secure the rug-base, a double oppositely-toothed rack fixed to the clamp or carrier and a double-

ended pawl pivoted with relation to the rack so that the ends may be made to engage with either one or the other of the racks, to move the clamp or carrier alternately to one side and the other of the table, a slide carrying said pawl, a treadle and intermediate mechanism connecting it with the slide, a needle-carrier having a needle working upwardly through the fabric, and connected with the treadle, a slotted yoke extending transversely across the table, a looper slidable in the yoke and having a horn which passes through the loop of the needle-thread when the looper is advanced, a bell-crank lever mounted in the yoke, a connection from one arm of said lever to the looper and a connection from the other arm of the lever to the treadle.

4. In a rug-making machine, a channeled table, a guide and clamp for holding the rug adapted to travel therein, a reversible reciprocating mechanism whereby the rug is carried alternately to one side and the other of the table, fingers or comb-teeth projecting horizontally from the front of the clamp above the fabric, a vertically-reciprocating needle adapted to move through the fabric and to carry a thread, a tension apparatus whereby said thread is drawn taut, a horizontally-movable looper having the horn which passes through the loop of the needle-thread when the looper is advanced, supporting-spurs upon which the horizontal yarn of the fabric is laid, and a tilting arm and hook pivoted within the horn, said hook adapted to engage the yarn and draw it through the needle-thread when the looper is withdrawn, said loop being tied by the needle-thread when the needle is withdrawn through the fabric.

5. In a rug-making machine, a slidable

clamp and carrier having teeth projecting forwardly therethrough and a mechanism by which it is reciprocated so as to present the spaces between the teeth successively to a vertically-movable thread-carrying needle, a horizontally-movable looper, mechanism by which the needle-bar and the looper are connected with the opposite end of a treadle whereby the two are movable in unison and a reversible feed mechanism connected with the same treadle so as to operate in conjunction with the needle-bar and the looper.

6. In a rug-making machine, a channeled table, a rug clamp and carrier and mechanism whereby it is moved alternately to one side and the other of the table, teeth projecting forwardly from the clamp above the fabric, a vertically-reciprocating needle movable through the fabric and a thread carried thereby, a tension device whereby the thread is drawn down and the needle is returned, a horizontally-movable looper having a projecting horn, a tilting hooked arm fulcrumed within said horn, supports for the horizontal yarn which is introduced upon the supports and beneath the horn so as to be engaged by the hook when the looper is advanced and withdrawn through the needle-loop when the looper is retracted, an arch extending across the looper-guide adapted to engage the hook-arm and tilt it when retracted so as to disengage the hook from the arm and leave the yarn-loop within the needle-loop.

In witness whereof I have hereunto set my hand.

OLIVER RICE.
